Inventor:
Otis R. Rust.

Thurston ^{by} Kivett Hudson
attys.

UNITED STATES PATENT OFFICE.

OTTIS R. RUST, OF CLEVELAND, OHIO.

BUCKLE.

Application filed May 9, 1921. Serial No. 487,987.

To all whom it may concern:

Be it known that I, OTTIS R. RUST, a citizen of the United States, residing at Cleveland, in the county of Cuyahoga and State 5 of Ohio, have invented a certain new and useful Improvement in Buckles, of which the following is a full, clear, and exact description.

The present invention relates to a buckle 10 which is particularly designed and intended for use in connection with a belt to be worn by a person and the object of the invention is to produce a buckle which will effect a tight locking and holding pressure upon 15 the belt when the buckle is in normal use, and further, to produce a buckle which will have the gripping element positively moved and held in gripping position and positively moved to ungripping position, and 20 thereby avoid any accidental release of the belt while the buckle is being worn.

Referring to the drawing, Fig. 1 is a top plan view with the outer or top plate removed; Fig. 2 is a sectional elevation; Fig. 25 3 is a sectional elevation with the buckle in non-gripping position; Fig. 4 is a side elevation; Fig. 5 is an elevation with portions of the buckle broken away; Fig. 6 is a section on the line 6—6 of Figs. 2 and 5; Fig. 7 is a side elevation of a portion of 30 a buckle of modified construction; Fig. 8 is a top plan view of a modified construction; Fig. 9 is a longitudinal section of a modified construction; Fig. 10 is a perspective 35 view showing parts of the buckle.

Referring to the drawings, 1 indicates an outer plate which will be called a face plate. This face plate is provided with downwardly extended flanges 2 and 3.

40 Cooperating with the face plate and its flanges, is a member which comprises a base plate 4 and having upstanding flanges 5 and 6. The base plate and its upstanding flanges may be assembled with respect to 45 the face plate and its inturned flanges by inserting the flanges 5 and 6 inside of the flanges 2 and 3. These flanges have a close fit and additionally, the inner portions of the flanges 2 and 3 are provided with 50 projections such as indicated at 1^a which fit in suitable slots formed in the side flanges 5 and 6 such as illustrated at 4^a in Fig. 5. The base member 4 has a portion thereof which is pivoted, this portion being 55 designated at 4^b in Fig. 3. Any desired

construction for pivoting this section may be employed and as shown a pin 4^c extends transversely between the flanges 5 and 6. The pivoted portion 4^b normally lies in substantially the same plane as the remaining 60 portion of the base 4 so that the inner surface of the buckle is a plain surface and offering no extensions or projections which may catch on the clothes of the wearer and possibly result in moving the operating 65 mechanism of the buckle to its open or ungripping position.

The pivoted member 4^b has upwardly extending flanges which are indicated at 4^d and 4^e, these flanges extending inside of the 70 flanges 5 and 6. Extending between the flanges 4^d and 4^e is a pivoted member 7 which has teeth 7^a and a rearwardly extended operating portion 7^b as shown in Fig. 3. This clamping member or gripping 75 member is adapted to receive one end of a belt strap which is indicated at 8, while the opposite end of the belt strap as indicated at 8^a, is operated on by the gripping mechanism to hold the same as will be later described.

Extending transversely between the flanges 5 and 6 of the base member is a gripping member 9. This gripping member has a 80 gripping face 9^a which may if desired be provided with projections, ribs or otherwise roughened to produce a better gripping effect, and this member is also provided with extensions or tail pieces 9^b, the function of which will be subsequently described. 85 This gripping member is mounted on a pin 10 which extends transversely between the side flanges 5 and 6, and the ends of the pin occupy diagonally extending slots 11 and 12, which are shown particularly in 90 Figs. 3 and 5. The ends of the pins are free to move in the slot and the ends may also turn so that the gripping member has not only a movement toward and from the face plate 1, but it may also have a pivotal 95 movement about the pin 10 as an axis.

Adjacent the gripping member is a link member 13 which at its forward end is pivotally mounted upon the pin 10 and at its rear end is pivotally mounted upon a pin 105 14 which extends between the side flange members 4^d and 4^e of the hinged portions 4^b of the base 4.

It will therefore be seen that the member 13 acts as a moving or driving element 110

2
between the hinged portion 4^b and the clamping member so that when the hinged portion 4^b is moved to its closed position, as when the buckle is worn, the gripping member is positively moved to its gripping position, and additionally the gripping member is maintained in its gripping position, so long as the buckle is being worn and the hinged portion 4^b maintained in its closed position.

10 It is also apparent that when the hinged portion 4^b is moved to open position as shown in Fig. 3, the gripping member is positively withdrawn from its gripping position and maintained in its open position so long as the pivoted portion 4^b is in its open position.

15 In order that the gripping member may be moved to its most effective gripping position, means are provided whereby the gripping member is tilted or moved about its pivot as it assumes its final gripping position. This is accomplished by providing projections 15 and 16 which extend inwardly 20 from the side flanges 5 and 6 and are so positioned that the extension or tail-pieces 9^b of the gripping member 9 will engage therewith when the gripping member is moved 25 forward toward its gripping position. By 30 the engagement of the ends of the member 10 in the slots 11 and 12 the gripping member is tilted so as to be moved to its most advantageous gripping position and maintained in this position by the parts which have 35 before been described.

40 In Figs. 7 to 10 there is shown a slightly modified form of buckle which however is only modified in so far as it relates to the means for positively tilting or moving the gripping member 9 about its pivot.

45 The base member shown in the figures mentioned is indicated at 20 and provided with the upstanding flanges 21 and 22. Each of these flanges is provided with a slot, one of which is indicated at 23, it being understood that the opposite flange has a similar slot. Extending between the flanges 21 and 22 and substantially lying against the base 50 is a member 24, which member is provided with projections 24^a and 24^b which extend through the slot before mentioned. The rear end of the member 24 is mounted on a pin 55 and the gripping member 26 is at the lower portion of the extension provided with ears, one of which is represented at 26^a which are pivotally mounted upon the pin 25.

55 The remaining portion of the mechanism is the same as that which was previously described.

60 Pivoted upon the member 26 is a link 26^b which at its opposite end is pivoted upon the hinged member 26^c.

65 When the gripping member is moved toward gripping position, it will in the initial stage of its movement push the plate 24

forward and the extensions 24^a and 24^b will come to the ends of the slots in which they are positioned. This then will definitely limit the movement of the member 24 and consequently any additional movement of the gripping member causes the gripping member to move with a tipping or pivotal movement so that the gripping member is moved into a substantially vertical position which is the position of its most effective gripping action on the belt or strap which is to be held.

70 Having described my invention, I claim—

1. A belt buckle comprising a face plate having depending flanges, a base plate having upstanding flanges, the flanges of one plate engaging with the flanges of the other, a gripping member carried entirely by the base member and means for moving the gripping member into operative and inoperative position.

75 2. A buckle comprising a face plate having depending flanges and a base member comprising a base plate with upstanding flanges, the flanges of the base plate cooperating with the flanges of the face plate and thereby forming a closed buckle structure, a gripping member located between the face plate and the base member and means for operating said gripping member.

80 3. A buckle comprising a face plate having depending flanges and a base member comprising a base plate with upstanding flanges, the flanges of the base plate cooperating with the flanges of the face plate and thereby forming a closed buckle structure, a gripping member located between the face plate and the base plate, said base plate having a pivoted portion and connections between said pivoted portion and the gripping member for 85 operating the same.

85 4. A belt buckle comprising a face plate having depending flanges and a base member comprising a base plate with upstanding flanges, the flanges of the base plate cooperating with the flanges of the face plate to form a closed buckle structure, a gripping member movably mounted on the base member, a portion of said base plate being pivoted and connections between the said pivoted portion and the gripping member for 90 operating the gripping member.

95 5. A buckle having a face plate and a base plate, a gripping member mounted between the said plates and movable toward and from the face plate and a pivoted member forming a portion of said base plate, means carried by the said pivoted portion for securing one end of a belt, said pivoted member being connected to the gripping member for positively moving said gripping member toward and from its gripping position.

100 6. A belt buckle having a face plate and a base plate, a gripping member mounted for movement pivotally and also movement

toward and from the face plate, means for moving the gripping member toward and from the face plate, and means for turning the gripping member about its pivot.

5 7. A buckle having a face plate and a base plate, a portion of said base plate being pivoted, a gripping member located between the base plate and face plate and movable toward and from the face plate and also 10 pivotally mounted, a connection between the said gripping member and the hinged portion of the base plate, whereby the gripping member is moved toward and from the face plate, and means whereby the gripping member is simultaneously moved about its pivot.

15 8. A buckle having a face plate and a base plate, and flange members extending between the face and base plates, a gripping member extending between said flange members and mounted so as to move toward and from the face plate, and means carried by the buckle for positively moving the gripping member toward and from the face 20 plate.

25 9. A buckle having a face plate and a base plate, and flange members extending between the face and base plates, a gripping member extending between the said flange members and mounted so as to move toward and from the face plate, a portion of the base plate being pivoted and connections between said pivoted portion and the gripping member for moving the same toward and from 30 the face plates.

35 10. A buckle having a face plate and a base plate, and flange members extending between the face and base plates, a gripping member extending between the said flange members and mounted therein for pivotal movement and movement toward and from the face plate, means for moving the gripping member toward and from the face plate, and means for simultaneously causing the gripping member to move about its 40 pivot.

45 11. A buckle having a face plate and a base plate, and flange members extending between the face and base plates, a gripping member extending between the said flange member and mounted therein for pivotal movement and movement toward and from the face plate, said base plate having a pivoted portion, means connecting the said 50 pivoted portion with the gripping member to move the gripping member toward and from the face plate, and means for simultaneously causing the gripping member to move on its pivot.

55 60 12. A buckle comprising a face member and a base member with intermediate flange members, said flange members being provided with oppositely disposed diagonal slots, a gripping member extending between the said flange members, means carried by

the gripping member which extends into said slots and permitting pivotal movement of the gripping member, means for moving the said gripping member with respect to the said slots, and means for causing the gripping member to move about its pivot as the gripping member moves to gripping position.

65 70 13. A buckle comprising a face member and a base member with intermediate flange members, said flange members being provided with oppositely disposed diagonal slots, a gripping member extending between the said flange members, means carried by the gripping member which extends into said slots, a portion of said base member being pivoted and means connecting the said pivoted portion with the gripping member to move the same with respect to the slots.

75 80 14. A buckle comprising a face member and a base member with intermediate flange members, said flange members being provided with oppositely disposed diagonal slots, a gripping member extending between said flange members, means carried by the gripping member which extends into said slots, a portion of said base being pivoted and a link pivotally connected with the said pivoted base portion and with the gripping 85 member.

90 95 15. A buckle comprising a face member and a base member with intermediate flange members, said flange members being provided with oppositely disposed diagonal slots, a gripping member extending between said flange members, means carried by the gripping member which extends into said slots, and permitting pivotal movement of the gripping member, a portion of said base member being pivoted, a link member pivotally connected with the pivoted portion of the base member and pivotally connected with the gripping member for moving the gripping member, and means adapted to engage with the gripping member to pivotally move the same when it is moved to gripping 100 position.

105 110 16. A belt buckle comprising a face member, a base member and intermediate side members, a gripping member which is mounted for movement toward and from the face plate and also pivotally mounted, said gripping member having an extension and means cooperating with said extension to move the gripping member about its 115 pivot when the gripping member moves to gripping position.

120 125 17. A belt buckle comprising a face member, a base member and intermediate side members, a gripping member which is mounted for movement toward and from the face plate, and also pivotally mounted, a transversely extending plate pivotally connected with the gripping member and means for limiting the movement of said plate 130

whereby the gripping member is moved about its pivot as it moves to gripping position.

18. A belt buckle comprising a face member, a base member and intermediate side members, a gripping member which is mounted for movement toward and from the face plate, and also pivotally mounted, a transversely extending plate pivotally connected with the gripping member, said plate

being provided with extensions and the said side members having slots in which said extensions extend, whereby the movement of the said plate is limited and the gripping member is moved about its pivot as the gripping member moves toward gripping position. 15

In testimony whereof, I hereunto affix my signature.

OTTIS R. RUST.
